UNITED STATES PATENT OFFICE.

WILLIAM F. HEINS AND JOHN HEINS, OF ALBANY, NEW YORK.

FUSE PLUG.

Application filed July 11, 1919, Serial No. 310,053. Renewed November 23, 1922.

To all whom it may concern:

Be it known that we, WILLIAM F. HEINS and JOHN HEINS, both citizens of the United States, and residents of Albany, in the 5 county of Albany and State of New York, have invented a new and Improved Fuse Plug, of which the following is a full, clear, and exact description.

This invention relates to fuse plugs and 10 has for an object to provide a plug in which the fuse may be removed and replaced without the use of tools.

Another object of the invention is to provide a fuse plug which may be readily taken 15 apart and cleaned.

A further object of the invention is the provision of a fuse plug wherein the contact normally resiliently grips the fuse while being easily removable.

20 A still further object of the invention is to provide a fuse plug with a removable hollow porcelain which presents a blow-out chamber.

Another object is to form the plug in such 25 a manner as to cause the burnt gases to slowly ooze out therefrom whenever the fuse "blows".

In the accompanying drawing:

Figure 1 is a side view of a fuse plug 30 closing an embodiment of the invention, certain parts being broken away for better disclosing the invention.

Figure 2 is a section through Figure 1 on line 2—2.

35 Figure 3 is a top plan view of the plug shown in Figure 1.

Figure 4 is a detail perspective view on an enlarged scale of the fuse and contact co-acting therewith, the same embodying cer- 40 tain features of the invention.

Figure 5 is a sectional view through Figure 2 on line 5—5.

Referring to the accompanying drawing by numerals, 1 indicates a body preferably 45 formed of porcelain. This body is constructed with a chamber or recess 2 open at one end and with threads 3 for receiving the threaded sleeve or shell 4. Shell 4 is secured to the depending flange 5 of the fibre cap 6 by any desired means, as for instance by spurs extending from the sleeve into the flange 5. As seen in Figure 2 the cap 6 is provided with a central opening 7 normally closed by a sheet of mica 8 resting against the shoulder 9 of cap 6. When 55 the body 1 is screwed into place in the shell

4 the end thereof firmly clasps or presses the mica 8 against shoulder 9. This forms a substantially gas tight joint at this point, but the gas may slowly escape through a 60 number of comparatively small openings 10 in the body 1, to the groove 11 and from thence along the outer surface of the body toward the closed end 12 of the body until it finally passes beyond flange 5. A small 65 opening 13 in shell 4 and a small notch or cut-out portion 13' in flange 5 act as guiding channels for the gas as it leaves the groove 11.

In the closed end 12 of body 1 is pro- 70 vided a square hole for receiving the contact member 14 which contact member is shown in detail in Figure 4. This contact member is formed with a contact 15 riveted or otherwise rigidly secured to a spring- 75 clasp or gripping member 16. This clasp is bent so as to produce facing hooks 17 and 18. These hooks are formed of resilient material and are positioned normally so that the ends will be slightly spaced apart. 80 However, when the clasp 16 is forced into position, as shown in Figure 2, the hooks 17 and 18 will be forced together and will consequently firmly grip the fuse 20 positioned therebetween near the hook end 19. 85 It is, of course, understood that the fuse may be of any size, capacity or shape without departing from the invention.

In operation, to assemble the plug the fuse 20 is bent for producing the hook 19 90 after which it is slipped into position as shown in Figure 4. The contact member with the fuse is then forced in the square opening in closed end 12 of body 1 until it reaches the position shown in Figure 2. 95 The free end of the fuse is then bent over the edge of the body 1 until it overlaps one or more of the threads 3, the fuse extending through a suitable notch 21 in body 1. After the fuse has been thus properly positioned 100 the shell 4 is screwed down over the body 1 until the open end of the body is pressing the mica window 8 tightly against the shoulder 9 of the cap 6. The plug is then ready for use and may be screwed in a 105 socket in the usual manner whenever desired. During the ordinary use of the plug air freely passes through the opening 13, cut-out portion 13', groove 11 and holes 10 into chamber 2. However, when there 110 is a sufficient overload placed on the line the fuse 20 will burn or "blow" and the gases

- will pass out in a reverse direction to the passage of the air into chamber 2. After the fuse has burned out and it is desired to renew the same, the body 1 is unscrewed and 5 the parts cleaned. By a slight pressure on the clasp 16 from within chamber 2 the entire contact member 14 will become removed whereupon a new fuse may be placed in position and the parts re-assembled. The 10 operation of taking the plug out, placing the fuse in position and the re-assembling of the parts requires no tools as this operation may be done better and more expeditiously by the hands of the operator.
15. What we claim is:
1. In a fuse plug of the character described, a hollow body having air and gas openings adjacent one end merging into a groove, a shell having an opening registering with said air and gas openings, a cap for the shell having a notch registering with the opening in said shell, said notch extending to a point exteriorly of the plug, a contact member carried by said body, and 20 a fuse in said hollow body engaging said contact member and said shell.
  2. In a fuse plug of the character described, a body having a closed end formed with a square aperture merging into a 30 chamber, and a threaded exterior, a removable contact member formed with resilient, slightly diverging fuse receiving hooks, said hooks being of such a size and so positioned as to be pressed together when forced into 35 said square aperture for gripping a fuse having one end extending between said hooks, a fuse member having one end grasped by said hooks and the opposite end overlapping some of the threads on said 40 body, said fuse member extending through
- said chamber, a shell screwed over said body on said threads, and an insulating cap carried by said shell, said cap covering one end of said body.
3. In a fuse plug of the character described, a body formed with a closed end and an open end, a pair of spring gripping contact members arranged in said closed end, a cap carried by said open end, a fuse formed with a hook at each end, one of said hook ends being engaged by one of said contacts and the hook thereof acting to prevent accidental displacement by pulling, the opposite end of said fuse having the hook part overlap said body and a metallic sleeve 55 threaded onto said body, and frictionally engaging said last-mentioned hook end whereby the fuse is locked at both ends against accidental displacement.
4. In a fuse plug of the character described, a body having a closed end and an open end, said open end having a radially extending aperture therein and also an exteriorly positioned groove merging into said aperture, said groove extending partly 60 around the body, a metallic sleeve carried by said body exteriorly thereof, a contact member carried by said closed end, a fuse connecting said contact member with said sleeve, said sleeve having an opening therein adapted to register with said groove and a cap fitted onto said body at the open end formed with a groove registering with the groove in the sleeve, said groove and said cap extending toward the closed end of the 65 plug so as to discharge the gas in a direction away from the open end of the body.

WILLIAM F. HEINS.
